UNITED STATES PATENT OFFICE.

HERMANN KIRCHHOFER, OF PARNASSUS, PENNSYLVANIA.

SHADE-BRACKET.

No. 805,973.

Specification of Letters Patent.

Patented Nov. 28, 1905.

Application filed November 5, 1904. Serial No. 231,468.

To all whom it may concern:

Be it known that I, HERMANN KIRCHHOFER, a citizen of the United States, and a resident of Parnassus, in the county of Westmoreland 5 and State of Pennsylvania, have invented a new and Improved Shade-Bracket, of which the following is a full, clear, and exact description.

The purpose of the invention is to provide 10 a neat, simple, and economic form of shade-bracket which can be secured to a window-casing at any convenient point between the longitudinal edges of the side members of the casing whether the shade to be hung has a 15 longer or a shorter roller than required for the window, thus not only enabling the brackets to be used in connection with different lengths of shade-rollers, but also enabling the brackets to be attached to the firmest 20 portions of a casing to which brackets have been previously many times applied.

Another purpose of the invention is to so construct the improved brackets that they may be quickly and conveniently adjusted 25 and firmly held in their adjusted position, rendering it possible for the brackets to remain as fixtures on the window-casing and effectively brought into service for the same length of roller or for a different length than 30 that for which they were originally planned.

The invention consists in the novel construction and combination of the several parts, as will be hereinafter fully set forth, and pointed out in the claims.

Reference is to be had to the accompanying 35 drawings, forming a part of this specification, in which similar characters of reference indicate corresponding parts in all the figures.

Figure 1 is a perspective view of a portion 40 of a window-casing, an improved bracket applied to the casing, and a portion of a shade supported by the bracket. Fig. 2 is a front elevation of the improved bracket. Fig. 3 is a plan view of the same, and Fig. 4 is an end 45 view of the bracket.

A represents a portion of a window-casing, B one of the improved shade-brackets, and C a portion of a window-shade supported by the bracket, the relations of the several parts 50 to each other being clearly shown in Fig. 1.

The improved fixture consists, primarily, of a clip-base α , adapted for attachment to a window-casing, a carrier α' , adjustable in the clip-base, and a bracket-arm α'' , connected with the 55 carrier.

The clip-base α is preferably made of spring

metal—sheet metal, for example—and may be of any desired shape. In the construction of the said clip-base the material is bent upon itself to provide a rear section 10 and a front 60 section 11, both of said sections having corresponding apertures 12 therein to receive nails, screws, or equivalent forms of fastening devices. Where the bend or fold is made in the material of the clip-base α a transverse eye 65 or socket 13 is produced, while at the free end of the front section 11 of the said base a transverse channel is formed in the rear face of said section, producing where the two members are brought together at their free ends 70 a second transverse socket 14. The back face of the rear section 10 is straight or flat, so that it will bear snugly against a casing or other support to which it is to be applied, and where the sockets 13 and 14 are formed the 75 outer face of the front member 11 of the said clip-base is rendered more or less convexed, as is shown in Figs. 2 and 4, as the sockets above mentioned are almost entirely produced in the inner face of the said front section 11. 80

The carrier α' , above referred to, consists of two parallel body members 15 and 16 and a connecting member 17, the body members 15 and 16 being adapted to lie between the two sections 10 and 11 of the said clip-base and to 85 slide in the sockets 13 and 14 of said base, and the bracket-arm α'' , which may be of any suitable form to receive trunnion of a shade-roller, is secured to the connecting member 17 of the carrier α' . Such attachment is usually effected 90 by carrying the material of the bracket-arm closely around and in locking engagement with the connecting member 17, as is shown in Figs. 2 and 3, thereby forming a sleeve 18.

A shade-bracket when constructed as above 95 described is light, simple, durable, and economic, and by its means a shade-roller may be mounted in the bracket-arms in a convenient manner either before or after the device is attached to its support, and when attached the carriers α' of the device may be adjusted as may be required to accommodate the bracket-arms α'' to a long or a short roller.

When the device is to be applied, the body members 15 and 16 of the carrier α' are passed 105 into the sockets 13 and 14, and then screws, for example, are passed through the apertures 12 in the clip-base and into the window-casing or other support, and when these screws are well driven into the support the two sections 110 of the clip-base α will be firmly held on the support and in contact with each other, thus

causing the carrier to be held stationary in the position to which it was adjusted. When another adjustment of the carrier is needed, it is simply necessary to loosen up the screws, 5 whereupon the body members of the carrier may be slid backward and forward in the sockets of the clip-base.

The connecting member 17 of the carrier a' is preferably flattened where the sleeve 18 10 of the bracket-arm a^2 engages with it.

Having thus described my invention, I claim as new and desire to secure by Letters Patent—

1. In shade-brackets, a clip-base formed of two sections overlying one another and adapted 15 to be secured together in flat engagement, one section having at each end a socket on its inner face, a carrier comprising straight parallel members and a connecting member, said parallel members having sliding movement 20 between the sections of the base-clip in the sockets thereof, and a bracket-arm secured to the connecting member of the carrier and projecting at right angles therefrom.

2. In shade-brackets, a clip-base constructed 25 in two spring-sections connected at one end and free at their opposite ends, one section having a socket formed at each of its end portions, said sockets facing the opposing section, a bracket-arm, means for securing the 30 free end of the sections together, and a carrier to which the bracket-arm is attached, the said carrier being provided with parallel members which enter the sockets in the clip-base.

3. In shade-brackets, a clip-base consisting 35 of a spring-plate bent upon itself, forming a rear section and a front section, both of the

sections having corresponding openings therein and the front section having sockets formed in its rear face, a carrier consisting of two parallel members, which enter and are adjustable in the said sockets of the clip-base, and a connecting member, and a bracket-arm secured to the connecting member of the carrier. 40

4. A shade-bracket, comprising a carrier 45 having spaced and parallel members, a bracket-arm secured to and projecting from one end of the carrier, and a clip-base formed of spring-sections connected at one end and free at the opposite ends, the free ends of the sections 50 being adapted to be secured together, the clip-base being provided at its ends with sockets in which the members of the carrier enter and are adapted to be clamped when the free ends of the sections are secured together. 55

5. A shade-bracket, comprising a carrier having spaced and parallel members, a bracket-arm secured to and projecting from one end of the carrier, a clip-base formed of two apertured spring-sections connected at one end 60 and free at the opposite ends, the clip-base being provided at its ends with sockets in which the members of the carrier enter, and screws for securing the base-clip in position and the sections thereof in flat engagement. 65

In testimony whereof I have signed my name to this specification in the presence of two subscribing witnesses.

HERMANN KIRCHHOFER.
